FAN DIFFUSER HAVING AN AIRFOIL LATTICE DEFLECTOR

Filed Sept. 20, 1949

UNITED STATES PATENT OFFICE

2,626,101

FAN DIFFUSER HAVING AN AIRFOIL
LATTICE DEFLECTORMorton B. Curley, Worthington, Ohio, assignor to
The Jeffrey Manufacturing Company, a cor-
poration of Ohio

Application September 20, 1949, Serial No. 116,705

2 Claims. (Cl. 230—120)

1

This invention relates to a fan and more particularly to a fan having a diffuser which is constructed to diffuse the output air from the fan by using airfoil lattice deflectors and in which a transverse dimension of the diffuser is substantially constant.

An object of the invention therefore is to produce a fan and associated diffuser having the above mentioned characteristics.

A further object of the invention is to provide a diffuser in which the cross-sectional area is increased as the air passes from one section thereof to another through a lattice deflector and in which one dimension of the diffuser, such as its width, may be substantially constant.

Other objects of the invention will appear hereinafter, the novel features and combinations being set forth in the appended claims.

In the accompanying drawings,

Fig. 1 is a combination sectional and elevational view in which the diffuser may be considered as rotated either ninety degrees or one hundred and eighty degrees from its actual installation position; and

Fig. 2 is a plan view of the fan and diffuser of Fig. 1.

In order to produce an efficient fan, such as used to ventilate a mine, it is well recognized that there should be a diffuser on the air output side of the fan, in which the cross-sectional area through which the air travels is increased between the discharge end of the fan proper, or, in other words, adjacent the blades, and the final delivery of the air either to atmosphere or to a conduit leading to a mine ventilating shaft, the first in the case of an exhaust fan, the latter in the case of a pressure fan. Generally, the ratio of this area is of the order of 3-3½ to 1. In other words, the effective cross-sectional area at the exhaust or output end of the diffuser is preferably from three to three and one-half times the effective cross-sectional area at its input end.

Heretofore, one accepted way of producing this desired ratio of cross-sectional areas in a diffuser has been to provide a frusto-conical diffuser which expands in diameter and in cross-sectional area from its input position, adjacent and to the rear of the fan blades and deflectors, if any, to its discharge position. Such construction is illustrated, for example, in my Patent No. 2,307,490, dated January 5, 1943.

In some installations this construction has been found undesirable for a number of reasons, all of which apply in some instances, others only some of them. One of the objections sometimes encountered is that the diameter of the discharge end of the diffuser is so much larger than the diameter of the fan proper, or its input section, that it is necessary to place the fan an

2

undesirable distance away from the adjoining structure and/or to require an extensive and undesirably high base or support for the fan proper.

Another objection often encountered is that these fans set alongside a building or a drift mine opening and it is necessary to excavate the hill or ground slope adjacent the opening to accommodate the fan. In such case sometimes considerable excavation is required because obviously if the fan is of the suction type the large discharge opening of the diffuser cannot be permitted to discharge directly into a closely adjacent upright or upwardly extending wall.

The diffuser of my invention overcomes these and other objections, while maintaining the desired ratio of area of diffuser input to output, in that a pair of side walls of the diffuser, or at least a substantial portion thereof, are parallel throughout the various sections of said diffuser and are not substantially greater, if any, than the corresponding dimension of the fan proper. Furthermore, a diffuser is so constructed that the longitudinal axes of the several sections thereof make obtuse angles with each other, thus making it possible to provide the overall diffuser as a turning unit so as to deflect the discharged air upwardly, laterally or downwardly, as circumstances dictate to be desirable. For example, in one typical installation the complete fan with diffuser may be placed closely adjacent a structure having a vertical wall with the fan proper setting close to the ground. If the fan is a suction type, that is, draws air out of the ventilating mine shaft, the deflector may have its discharge opening extending upwardly so that any hill or wall to the rear of the deflector will in no wise interfere with the free discharge of the air. In another typical installation the fan unit might be set close to the ground and the deflector turned either laterally or downwardly, forcing air into a mine shaft casing or to atmosphere.

Referring specifically to the accompanying drawings, a radial blade or propeller type fan is provided, including a fan casing or housing 10 having a frusto-conical converging air inlet portion 11 and a generally cylindrical portion 12 adjacent the rotor 13 of said fan, which rotor may, for example, follow the construction in my Patent No. 2,307,490 above identified. The rotor 13 includes radially extending blades 14 and is mounted on a drive shaft 15 carried in appropriate bearings, one of which is seen at 16, mounted on a pedestal 17. The other bearing for shaft 15 is mounted in a cowling 18 mounted in part within the casing 10. The pedestal 17 is provided with a mounting base, as is the casing 10, so that the fan unit proper, including the

parts above described, may be mounted on any desired base or foundation, such as a concrete base.

The fan illustrated is of the blower type; that is, it draws in atmospheric air and forces the air ultimately to a mine shaft casing, or the like. If desired, it may be of the exhaust type in which the inlet portion 11 will be connected with the ventilating mine shaft, or the like, in a well known manner. In any case, whether the fan proper is of the exhaust or pressure type, it is preferably provided with a diffuser which in its entirety is designated by the reference character 19, which diffuser has the function of converting the kinetic energy of the moving air to an appreciable extent to static energy or pressure which is essential to maintain high efficiency in the overall unit.

As illustrated in the drawings, the diffuser 19 is made up of four sections, the first diffuser section being designated 20, the second 21, the third 22 and the fourth 23. Diffuser section 20 performs two principal functions. First of all, in cooperation with the tail portion of the cowling 18 it increases the effective cross-sectional area from its input to its output. For example, the effective input area of the diffuser section 20 in one typical illustration, which will be followed through purely as an example of a practical construction, is 9.41 square feet. This means that the effective input area through which the air can flow at the left-hand side of diffuser section 20, as viewed in Figs. 1 and 2 of the drawings, is 9.41 square feet. This is the area of the opening into said section 20, less the area of the cowling 18 at said opening.

The output area of said section 20, which is the area adjacent the right-hand side, is 12.65 square feet. It is to be noted that the axis of the air travel through the section 20 is not changed and, as illustrated in the drawings, is substantially perpendicular to a plane through the output area of said section 20.

The discharge area of the section 20 is, of course, equal to the input area of the section 21. A characteristic of sections 21, 22 and 23 is that opposite elements of the side walls are parallel though generally unequal in length, and the direction and volume of the air flow through each section is constant for the entire section, except for the airfoil lattice deflectors which may be considered for practical purposes as separate from the sections themselves. In this connection it may well be stated at this time that there is an airfoil lattice deflector 24 interposed between the sections 21 and 22, and a similar deflector 25 interposed between sections 22 and 23.

Reverting to a consideration of the parallelism between opposite side walls of each section 21, 22 and 23 within itself, it is to be noted that as illustrated in Fig. 2 of the drawings the two lateral sides of said section 21 are parallel and spaced apart, constituting vertical side walls. The bottom wall of this section is a substantially horizontal flat wall designated by the reference character 26 (see Fig. 1). The top wall of this section 21 has substantially zero longitudinal dimension and this must not be confused with the upwardly sloping top wall, as viewed in Fig. 1, which constitutes in effect the wall of the lattice deflector 24 which, as here illustrated, is built in as an integral part of the section 21, though functionally it must be considered as separate therefrom.

From the above description of section 21 it is obvious that its input is rectangular in cross-section and consequently the adjacent continuing wall or end of the section 20 must likewise be rectangular. It is further evident from the above description that the forward or left-hand end of the section 20 is round. Consequently the diffuser section 20 not only acts as the first step in the diffusing function, but also is a transition piece connecting the round discharge opening of the fan section 12 with the rectangular input opening of the diffuser section 21.

The longitudinal axis of the section 21 coincides with the longitudinal axis of the section 20 and thus there is no change in the direction of the air in moving from section 20 to section 21. The discharge end of the section 21 is, of course, the same size as the input or receiving end of section 22 and they are joined along a plane which makes an acute angle with the longitudinal axis of said section 21. The angle of this plane with a plane at right angles to the longitudinal axis of the section 21 is generally designated in the art by the Greek letter β (beta). This angle is known in the art as the stagger angle.

As previously mentioned, elements of opposite side walls of the section 22 lie in parallel planes. The cross-sectional area of this section 22 is herein to be understood as the area of a plane to which the axis of said section is perpendicular and which intersects at right angles the four right angularly related sides of said section 22 or projections or extensions thereof. In the illustrative embodiment of the invention this cross-sectional area of section 22 is fixed at 20.5 square feet. The above definition of "cross-sectional area" also applies to sections 21 and 23.

The air in passing from the section 21 to the section 22 is deflected by the airfoil lattice deflector 24, and the direction of travel of the air in passing through the section 22 is substantially along the longitudinal axis thereof which is designated by the arrow in said section. The angle between the direction of travel of said air in section 22 and its direction of travel in section 21 is designated as θ (theta) in this art and is known as the turning angle.

It may be stated that there is a recognized relation in the art between the cross-sectional areas of two such adjacent sections through which air must travel and the turning angle and the stagger angle which is expressed by the equation:

$$\frac{A_{22}}{A_{21}} = \frac{\cos(\beta - \theta)}{\cos \beta}$$

In this case the ratio of A_{22} to A_{21} is:

$$20.5 : 12.65 = 1.62$$

From this it is possible to pick out a desired relation of the turning angle to the stagger angle from standard charts for any given solidity of the lattice deflector.

The deflector section 23, as above mentioned, also has opposite side walls lying in parallel planes. The cross-sectional area of this section is increased over the cross-sectional area of section 22 and in the illustration given the ratio is 1.62 to 1, the same as the ratio between sections 22 and 21, so that the cross-sectional area of section 23 is 33.2 square feet.

To reiterate briefly, the cross-sectional area, or, in other words, the area at right angles to all the side walls of the section 22, is 20.5 square feet, which is 1.62 times the cross-sectional area of section 21.

The cross-sectional area of section 23 is likewise 1.62 times the cross-sectional area of section 22. Therefore, each succeeding section 21, 22 and 23 has a greater cross-sectional area than the preceding section. Furthermore, the area of each section 21, 22 and 23 is uniform within that section itself. In order for the sections 21, 22 and 23 to be joined together so that the output perimeter of a preceding section is the same as the adjoining input perimeter of a succeeding section, the longitudinal axis of each succeeding section 22 and 23 makes an obtuse angle with the axis of each preceding section. As a consequence of this, as the air progresses from section 21 to section 22 to section 23 it is inherently deflected so that the diffuser function is carried out simultaneously with a change in direction, making it possible and practical to turn the direction of flow of the air as it is simultaneously diffused, thus maintaining the desired efficiency of the fan.

As above pointed out, the input area of the first diffuser section 20 was 9.41 square feet. The uniform cross-sectional area of the diffuser section 23 was 33.2 square feet. The ratio of the area of section 23 to the input area of section 20 is:

$$33.2 : 9.41 = \text{approx. } 3.5$$

which is the desired ratio of expansion of the air within the diffuser consistent with high efficiency for the fan as previously set forth.

It may be noted that after the air leaves the airfoil lattice deflector 25 it is not further expanded in the casing section 23 and it might be suggested that since there is no further expansion in this section that it serves no useful purpose, particularly where the fan is of the exhaust type and discharges from the diffuser to atmosphere. In other words, it might be suggested that the air simply be discharged from deflector 25 to atmosphere. It has been found, however, that it is very desirable to provide such a uniform cross-sectional area of the casing section following the final lattice deflector.

In case the fan is of the exhaust type and it exhausts to atmosphere there is no occasion to attach any other casing section to the diffuser section 23. As illustrated, particularly in Fig. 1 of the drawings, however, the fan is shown as of the blower type and consequently there is a casing section 27 attached to the diffuser section 23. The casing section 27 is not intended to have any diffuser function but merely acts as a casing to deliver the properly diffused air to a mine shaft ventilating conduit, housing, or the like.

From the above description it is obvious that a fan, such as a mine ventilating fan, either of the exhaust or pressure type, has been provided, in which the diffuser is so constructed that it may be placed conveniently in positions which heretofore have produced structural problems, particularly in that the diffuser need not have substantially greater width or lateral horizontal dimension than the fan proper and that the discharge opening of the diffuser may extend upwardly, thus not requiring any elevating base for supporting the fan or the deflector and radially deflecting the air, if discharged to atmosphere, upwardly or in a direction that an adjacent building, hill or mountain slope, or the like, will not interfere with the free discharge of said air. Likewise the diffuser construction in the case of a pressure or blower fan provides for inherent turning of the housing which directs the air into the mine shaft conduit or housing, readily lend-

ing itself to an installation where such is incorporated in a mine shaft and extending downwardly into the ground. It has been found that there are numerous problems created by field conditions in which the arrangement of my invention is a very effective solution and greatly reduces the total overall cost of an installation without in any way sacrificing the efficiency of the fan.

- 10 In the illustration given there are four sections to the diffuser and two airfoil lattice deflectors which are between the last three sections which effect a change of air direction. This number is found desirable in the illustration given. In 15 some installations it is possible that only a single lattice deflector may be required between two diffuser sections. It is possible that in some installations three such deflectors will be required. In this regard it is to be noted that there is an airfoil lattice deflector at each position where adjoining sections have their longitudinal axes angularly related.

Obviously those skilled in the art may make various changes in the details and arrangement 25 of parts without departing from the spirit and scope of the invention as defined by the claims hereto appended, and applicant therefore wishes not to be restricted to the precise construction herein disclosed.

- 30 Having thus described and shown an embodiment of the invention, what it is desired to secure by Letters Patent of the United States is:

1. A fan including a discharge diffuser having a minimum input to output cross-sectional area 35 ratio of about three to one, said diffuser having at least two substantially parallel side walls throughout its length and having adjacent sections whose longitudinal axes make an obtuse angle with each other, and an airfoil lattice deflector between said adjacent sections of said diffuser.

2. A radial blade type fan including a casing having a generally cylindrical portion adjacent the fan blades, a diffuser including a first section 45 connected to the output side of said cylindrical casing portion in the direction of air flow, said first section being generally cylindrical at its input end adjacent said cylindrical casing portion and rectangular adjacent its output end and increasing in effective cross-sectional area from its input end to its output end, a second diffuser section connected to said first section and having a longitudinal axis coinciding with the longitudinal axis of said first section, a third section 50 having a substantially constant cross-sectional area greater than the cross-sectional area of said second section and connected with the output side of said second section, said third section having a longitudinal axis making an obtuse angle with the longitudinal axis of said second section, and an airfoil lattice deflector between said second and third sections.

MORTON B. CURLEY.
